UNITED STATES PATENT OFFICE.

WILLIAM P. STUART, OF CHICAGO, ILLINOIS.

ADJUSTABLE GRADE-LEVELER.

SPECIFICATION forming part of Letters Patent No. 240,784, dated April 26, 1881.

Application filed January 20, 1881. (No model.)

To all whom it may concern:

Be it known that I, WILLIAM P. STUART, a citizen of the United States, residing at Chicago, in the county of Cook and State of Illinois, have invented a new and useful Adjustable Grade-Leveler for Leveling and Grading Railroads and for other Purposes, of which the following is a specification.

This invention relates to grade-levelers for grading and leveling grades for double tracks, sidings, and other grading on railroads.

The objects of my invention are, first, to provide an adjustable removable grade-leveler for railroads, to be used in leveling grades for double tracks or sidings and all other grading necessary in building double tracks, sidings, or other road-beds of railroads; second, to furnish a device to keep a railroad-track clear and clean from weeds, grass, and other vegetation usually on the sides of the track; third, to provide an adjustable removable roller for rolling and pressing the grade and marking the line for lining the ties in the construction of railroad-tracks; and, fourth, to furnish a center-marker to mark the center of the railroad-track to be laid. I attain these objects by the mechanism and the particular arrangement, construction, and combination of the several parts, as illustrated in the accompanying drawings, in which—

Figure 1, Sheet No. 1, is a plan view of my invention. Figs. 2 and 3, Sheet No. 1, are cross and side views of the adjustable attachments of the roller. Fig. 4, Sheet No. 2, is a side view of my invention. Fig. 5, Sheet No. 2, is a view showing the shape of the forward end of the blade C. Fig. 6, Sheet No. 3, is an end view of my invention. Fig. 7, Sheet No. 3, is a sectional view of the construction and arrangement of the adjustable attachments of the leveler B to the car A. Fig. 8, Sheet 3, is a front view of the same. Fig. 9 is a cross-section of the same.

Similar letters refer to similar parts through the several views and drawings.

A represents a railroad-car provided with the usual running-gear, which is an ordinary flat or gravel car, or otherwise, and is constructed sufficiently strong to sustain the several attachments.

B is the adjustable removable leveler attachment, and is composed of a blade, braces, and connections.

C is the blade of the leveler attachment, and is made of boiler or tank iron or steel, having a sharp lower edge, turned in the manner of a shears, and is beveled or cut off at its forward end, as shown in Fig. 5, Sheet 2, to escape the ties of the main track or other obstructions.

D are braces or stiffeners, made of iron or any suitable material, and are rigidly attached at their outer ends to the blade C, and at their inner are adjustably and removably connected by guide-hinges and screw-connections to the sides of the car A. These braces may be of any number, and they differ in length, the shortest being at the forward end of the car and increasing to the rear. The sides of the car A and the rear brace, D, form the sides of a right-angle triangle, the blade C being the hypotenuse. The braces may be of any length desired. The blade C is connected at its forward end to the side of the car A by the same adjustable removable connections as the braces D. If desired, a very short brace may be used with similar connections.

The leveler B, by reason of its adjustments and connections to the sides of the car A, swings up and down on its hinges to any angle, being guided by the wire rope R; and whenever desired it can be raised or lowered on a level to accommodate itself to any grade, or the same may be entirely removed or detached from the car.

E is a rod running from the forward end of the car A to any part of the blade C, and loosely attached at its ends. It is provided with a reversible screw-nut, F, which allows it to accommodate itself to the height of the leveler B. This rod is for the purpose of holding B in a level position. Any number of these rods may be used.

G is an adjustable removable iron roller attached to the rear brace, D, and so connected therewith that it is adjustable to any distance required below the line on a level with the lower edge of the blade C, and also can be moved to the right or left, as may be desired. The edge of said roller makes a mark for the lining of the ties. The roller is provided with

a projection, H, encircling its center, which projection is called a "center-marker," and is for the purpose of marking the center of the grade at any distance from the center of the main track, as may be desired. H is cast with the roller G, or may be soldered thereto or attached in any appropriate manner. When not needed the roller can be readily removed, and it may be of any desired length.

10 K is a removable frame-work on the rear end of the car A, constructed of two uprights, O O, and cross-arms p p, which are properly braced and sufficiently apart to admit the rear brace, D, between them when the leveler B is folded up. The uprights O O rest in sockets I I on each side of the car, so as to be firm and yet allow the frame-work to be removed. Sockets I are also placed at the other end of the car, so that the frame-work K can be placed at 20 either end or removed from one to the other at will and without delay. The frame-work K supports and contains the necessary gearing, pulleys, and attachments to elevate and lower or swing the leveler B, as shown. This frame-work may be of any other suitable construction for the purpose.

15 L L are pulleys at the top of the frame-work K, and so placed as not to interfere with the folding up of B, and at a proper distance 30 from each other to do the work.

M is a crank attached to the frame-work K, and is provided with a cog-wheel, n.

P is a drum, around which the rope R works or winds, and has attached to its side a cog-wheel, k, which works in connection with n. They both revolve on shaft or pinion g.

25 R is a wire rope attached at or near the outer end of the rear brace, D, running thence over the pulleys L L to the drum P, around 40 which it is wound, or to the sheave-block S, and thence to the locomotive.

S is a sheave-block, through which the rope R runs to the locomotive, whereby the locomotive can be used as power in lieu of the 45 windlass.

T T are guide-hinges fastened to the side of the car A, one for each brace and one for the forward end of the blade C. In these hinges the ends of the braces D and blade C swing and 50 are adjusted. The hinges T are provided with screws d, having heads f, whereby the braces and blade are held in any position necessary to raise or lower the leveling of the grade, and whereby the leveler B may be removed 55 or adjusted without delay whenever desired.

Both sides of the car A can be provided with the hinges T, and with the same so arranged that the leveler B can be attached to either 60 side, and the point of the blade C be in either direction on either side, as the occasion requires, the leveler B being removed from one side to the other and from end to end, as desired, thereby avoiding the necessity of carrying the car to a switch or turn-table to reverse 65 the same, the frame-work K being moved from one end of the car to the other and reversed

to accommodate itself to the changing of leveler B.

V is a pin or catch to prevent the leveler B from falling when folded up and not in use.

70 X is a locomotive. The locomotive, which conveys the car, with attachments, to the point to be used, furnishes the power to operate the same.

75 My attachments to the car A are so arranged that they will not interfere with the car being used to carry gravel and other material.

The operation of this device is as follows: After the gravel and other grading material is dumped along the side of the main track for 80 the road-bed of the double track or sidings, the car A, with my attachments, is hauled to any point to be leveled and graded, the pin V is moved so as to allow the leveler B to swing, the crank M is turned, and the leveler B lowered to any angle desired. The locomotive connected to the car A is started, when the blade 85 C will level the grade and the roller G will roll and press the same, and at the same time the roller will mark the line for lining of the ties, and also, by means of H, will mark the center of the road-bed. If the resistance is too great, by turning the crank M the wire rope 90 R will immediately elevate the leveler B to any inclination, and it may be thus raised and lowered as desired. To raise and lower B on 95 a level to accommodate it to any grade, or to remove the same to attach it to the other side of the car, or for any purpose, the head f of the screw d is turned sufficiently to make the adjustment or removal, F being turned to allow E to accommodate itself. To keep the sides 100 of the track clear of weeds, grass, and other vegetation, the same operation is pursued as before. When the work is finished the leveler 105 B is folded up by turning the crank M, its rear brace, D, will rest between the uprights of the frame K, and B is held secure by the pin V, and the car is carried to the shop or to any 110 other point desired.

110 My invention can be operated by a small number of men, and is a great saving in time and labor.

What I claim as new, and desire to secure by Letters Patent, is—

115 1. The adjustable removable leveler B, provided with blade C, braces D D, and connecting-hinges T, in combination with car A and hoisting-rope R, substantially as shown and described, and for the purpose set forth.

120 2. The adjustable removable roller G, provided with center-marker H, in combination with leveler B, substantially as described and shown, and for the purpose set forth.

125 3. A removable frame-work, K, provided with a hoisting-rope, R, and hoisting-gearing, as constructed and arranged in combination with a grade-leveler and car, whereby the leveler is raised or lowered, substantially as shown and described.

130 4. The pin V, in combination with leveler B and frame-work K, whereby the leveler B is

held secure when folded up, substantially as described and shown.

5. The combination, in a grade-leveling device, of the leveler B, provided with blade C, braces D D, hinges T, with screws d and heads f, rod E, with nut F, roller G, with center-marker H, hoisting-rope R, frame-work K, with uprights O O, arms p p, pulleys L L, crank M, with wheel n, drum P, with wheel k, pinion g, sockets I, pin V, and car A, all substantially

as shown and described, and for the purposes set forth.

6. The guide-hinges T, provided with screws d and heads f, in combination with the car A, leveler B, and braces D, substantially as shown 15 and described.

WILLIAM P. STUART.
